UNITED STATES PATENT OFFICE.

EDWARD M. STILES, OF MOUNT PLEASANT, IOWA, ASSIGNOR TO U. S. SLICING MACHINE COMPANY, OF CHICAGO, ILLINOIS, A CORPORATION OF ILLINOIS.

MEAT-STACKER.

1,231,960.

Specification of Letters Patent.

Patented July 3, 1917.

Application filed February 5, 1915, Serial No. 6,198. Renewed May 14, 1917. Serial No. 168,589.

To all whom it may concern:

Be it known that I, EDWARD M. STILES, a citizen of the United States, residing at Mount Pleasant, in the county of Henry and 5 State of Iowa, have invented certain new and useful Improvements in Meat-Stackers, of which the following is a specification.

This invention relates to improvements in meat stackers for stacking slices of meat as 10 they are delivered from the meat slicer, and one of the objects of the invention is to provide an improved stacker having means for collecting and stacking the slices as they are cut, thereby obviating the necessity of collecting and stacking the slices by hand.

A further object is to provide an improved machine of this character, embodying a conveyer having impalement pins or prongs for receiving the flexible thin slices from the 20 cutter as they are cut, to convey the slices over a curved surface and then in a substantially straight line into a position to be delivered from the conveyer, the pins or prongs remaining in engagement with the 25 slice as it is passed over the curved surface, and also during its movement in the substantially straight line, the points of the pins or prongs, or the portions thereof which are in engagement with the slice, being always 30 maintained in such relation that the space between adjacent pins will not vary, during the entire traveling motion of the pins and conveyer.

A further object is to provide an improved 35 machine of this character, having means for delivering the slices from the conveyer and piling them upon a collector support.

To the attainment of these ends and the accomplishment of other new and useful objects, as will appear, the invention consists 40 in the features of novelty in substantially the construction, combination and arrangement of the several parts, hereinafter more fully described and claimed and shown in 45 the accompanying drawings illustrating the invention and in which

Figure 1 is a top plan view of a portion of a slicing machine, having an attachment applied thereto, constructed in accordance with 50 the principles of this invention.

Fig. 2 is a top plan view of the stacker showing the parts in another position with respect to Fig. 1.

Fig. 3 is an elevation taken on line 3—3, 55 Fig. 2.

Fig. 4 is an enlarged detail sectional view taken on line 4—4, Fig. 1.

Fig. 5 is an enlarged detail sectional view taken on the line 5—5, Fig. 3.

Fig. 6 is an elevation of the supporting 60 frame for the conveyer.

Fig. 7 is an enlarged detail sectional view taken on line 7—7, Fig. 1.

Fig. 8 is an enlarged detail sectional view taken on line 8—8, Fig. 1. 65

Referring more particularly to the drawings, the numeral 10 designates generally the supporting base of a slicing machine, having mounted thereon the usual cutter 11, and the reciprocating meat support 12, and 70 an operating crank 13, through the ordinary and well known gear connection, operates the cutter 11, and a gear 14 with which latter gear is connected an arm 15 and this arm in turn is connected by a link 16 with the 75 reciprocating support 12 and during the reciprocating movement of the support 12, the supplementary support 17 is fed forwardly by means of the rotatable feed screw 18 to present the meat to the cutter 11, all as 80 are well known in this art and form no part of the present invention.

Arranged adjacent the cutter 11, is a conveyer, designated generally by the reference numeral 19 in Fig. 5 and this conveyer is 85 supported by a frame work shown more clearly in Fig. 6, the frame work preferably comprising a base 20 and superposed spaced members 21, 22 and these members are preferably of a triangular configuration with 90 portions cut away for the sake of lightness.

The member 21 is supported above the base 20 by means of upright tubular elements 23 and the member 22 is supported above the member 21 by similar tubular elements 23, any number of which may be provided and the parts are fastened together preferably by means of tie rods or bolts 24, which pass through the members and the tubular elements. 100

The frame thus formed is arranged adjacent the front of the machine and in proximity to the cutter 11 so that one face of the frame will extend along the path of movement of the support 12, and arranged 105 adjacent another face of the frame is a collector support 25, to be hereinafter described. Mounted in suitable bearings, preferably carried by the members 21, 22 are rollers 26, 27 and 28 and these rollers are 110

preferably arranged in pairs respectively connected by upright axles 29, 30 and 31 and the ends of these axles are journaled in suitable ball bearings 32.

5 One pair of rollers is preferably arranged adjacent each corner of the frame and passing over the respective series of rollers, which are spaced from each other, are endless flexible belt elements 33, 34 and these. 10 belt elements are connected by spaced upright pin carrying elements 35. The ends of these elements are offset as at 36, formed by bending the ends of the element laterally with respect to the element and the extremities of these portions 36 are again bent 15 in a direction as at 37, to be substantially parallel with the body portion of the element, and the extremities 37 are arranged adjacent the outer faces of the belt elements 33 and 34 to be secured thereto. The 20 axles 29, 30 and 31 connecting the rollers 26, 27, 28 respectively are of a diameter considerably smaller than the diameter of the rollers so that when the flexible conveyer 25 elements 33 and 34 are traveling, they will move the pin carrying elements 35 so that they will pass over or around the rolls 26 after which the elements 35 will travel in a substantially straight line.

30 During the traveling movement of the conveyer, the spaces between the points of the pins or prongs 38 on adjacent elements 35, will be always maintained the same, that is the distance between adjacent pins will 35 not vary, whether the elements 35 with their associated pins are traveling in a straight line or over the curved surface, and this is rendered possible because the extremities of the pins or prongs 38 are always 40 maintained in a substantially direct straight line with the drive elements 33, 34, as shown clearly in Figs. 4 and 5, but the body portions of the elements 35 will be allowed to assume positions close together as they are 45 passing over the curved surface.

With this construction it will be manifest that when the prongs or pins 38 pick up the thin flexible slice as it is cut, and convey it away from the cutter, the first movement 50 of the slice when the pins or prongs engage it, is over a curved surface, and then in a substantially straight line after passing that surface. By maintaining the spaces between the points of the pins or prongs against variation at all times, and while they are in contact with the slice, it will be manifest that the slice will not become torn, stretched or distorted, but will be maintained against distortion during its movement upon the 55 conveyer, and at all times during the movement of the conveyer.

For the purpose of strength, rigidity and lightness, the elements 35 may be formed of sheet material, and the body portions bent 60 into the form shown at 39 in Fig. 5. The

pins or prongs may be secured to the element by passing them through the apex of the bent portion of the body of the element 35 and from the rear, and then fastened in any suitable manner, so that the extremities of the pins or prongs will terminate in a substantially straight and direct line between the belts or flexible elements 33, 34. 70

Any number of these elements 35 may be provided, and in order to maintain the conveyer against a slipping movement lengthwise of the axis of rotation of the rollers, if it is desired, flanges 40 may be provided on some of the rollers. 75

In the present form of the invention, the conveyer elements 35 are given a forward and backward reciprocating movement, in directions substantially parallel with the direction of the reciprocating movement of the support or carriage 12, and this movement may be accomplished in any desired or suitable manner, such as by means of an arm 41, (see Fig. 1), which is preferably connected with the support 12 to project beyond the front edge thereof and into a slot 42 provided in an upright member 43, which latter is preferably connected with the endless elements 33, 34, so that when the support 12 is moved forwardly to effect a cutting operation of the article, the conveyer elements 35 will be correspondingly moved to receive the slice from the cutter as it is cut, and when the support 12 moves backwardly, for the next cutting operation, the conveyer elements 35 are correspondingly moved so as to receive the next slice as it is cut. The connection between the arm 41 and the conveyer is so arranged as to permit the proper operation of the conveyer and the positioning of the elements 35, 105 to have the slice removed from the latter in a manner to be set forth. 95

A scraper 44 (see Fig. 1) is arranged adjacent the portion of the cutter where the cutting operation is effected and this scraper 110 is supported in any suitable manner, preferably from the chain box 45 of the machine and supported by the scraper is a curved guard or shield 46, which stands adjacent and in close proximity to the extremity of 115 the teeth or prongs 38, as the latter are moving over the pulleys 26. This scraper 44 serves as a means for preventing the thin slice from adhering to the cutter and the curved guard or shield 46 serves the purpose of maintaining the slice in engagement with the prongs 38 as the latter pick up the slice and also prevents the slice from being thrown off of the conveyer during the movement of the latter, inasmuch as there is always more or less momentum, which might tend to throw the slice from the conveyer. 120 The shield 46 is curved as shown and is so arranged that the extremities of the prongs will travel in close proximity thereto to in- 125 130

sure their impaling the slice and taking it away from the cutter as it is cut.

During the cutting operation, the support 12 will be traveling toward the left in Fig. 1 as will also the elements 35 and as the slice is cut it will be taken up by these elements and carried away from the cutter. During this cutting operation and the receiving of the slice, the elements will travel over the 10 curved surface formed by the rollers 26 as shown in Fig. 5, and then convey the slice in a substantially straight line and which line is formed by the rollers 26, 28, to carry the slice into a position to be delivered upon 15 the collector support 25, in which position, the slice is lifted from the conveyer, out of engagement with the pins or prongs 38 and delivered to the support 25.

In order to effect this dumping operation 20 of the slices, so that they will be superposed upon the support 25, it is desirable that the conveyer be arrested momentarily in its movement, and this will always insure the delivery of succeeding slices from the conveyer at the same place upon the support. 25 This is accomplished by taking advantage of the interval of rest which occurs in the reciprocation of the support 12 when it changes its direction of movement, or at the 30 point where the arm 15 which is connected with the gear 14, is passing over the dead center, and the interval of rest is therefore imparted to the conveyer, inasmuch as the conveyer is connected with the support 12 35 and its movement is responsive to the movement of the support 12.

To remove the slices from the conveyer, any suitable means may be employed, such 40 for instance as a fly 47 having a body portion and a series of fingers 48. This fly is mounted for rocking movement by means of a suitable bearing 49, secured preferably to the member 21 of the supporting frame, and the fingers 48 extend between the pins or 45 prongs 38 in directions lengthwise of the conveyer, and terminate adjacent the rollers 26, and the extremities of the fingers are curved or bent as at 50 to permit the slices carried by the conveyer to pass over the 50 extremities of the fingers. These fingers are arranged adjacent the base of the prongs or pins, preferably in close proximity to the body portion 39 of the elements 35 and some distance from the extremities of the pins.

55 In order that the fingers will assume this position with respect to the prongs, the end of the body of the fly adjacent the bearing 49 is bent or offset as at 51, to conform to the contour of the elements 35.

60 During the interval of rest of the conveyer, the fly 47 is rocked about its pivot 49 into the position shown in dotted lines in Fig. 4 to dump the slice upon the collector support 25, and after this dumping operation, the fly is returned to its normal posi-

tion in any suitable manner such as by means of a spring 52, (see Fig. 2). This dumping or rocking movement of the fly may be effected in any suitable manner, but a simple and efficient means utilizes the gear 14, upon 70 which is provided a cam portion 53 so arranged that as the arm 15 is passing over the dead center, this cam 53, or the high portion thereof, will engage an arm 54 on a rock shaft 55, the latter being mounted in suitable bearings 56 and having connected therewith an upright 57, which is in turn connected by means of a suitable link 58 with the fly as at 59, and the cam 53 will rock the fly against the tension of the spring 52.

Thus it will be seen that as the slice is cut, it will be taken up by the conveyer and carried away from the cutter into a position to be delivered upon the collector support 25, and when the conveyer with the slice 85 thereon reaches this position, it will be momentarily arrested in its motion, and during this interval of rest, the cam 53 will operate the fly to remove the slice from the conveyer and deposit it upon the collector support. 90 After the slice has been thus delivered, the cam will pass out of engagement with the arm 54 and the fly will resume its normal position, and the conveyer and support 12 will be moved back to their starting positions as soon as the arm 15 passes over the dead center, to cut and convey away another slice to be similarly delivered to the collector support 25 and superposed upon the slice last delivered to the support 25.

100 Unless provision is made to compensate for the increasing size of the stack of slices on the support 25, it will be manifest that the slices would not be piled properly, therefore, the collector support 25 in the present form of the invention comprises a platform upon which the slices are delivered and this platform has depending therefrom a plurality of uprights 60, any number of which may be provided, and these uprights have 105 heads 61 provided on the free extremities thereof and telescope into tubular uprights 62, which latter are formed with shoulders 63 to prevent the disengagement of the uprights 60 from the tubular member 62.

110 Springs 64, any number of which may be provided, are arranged beneath the platform 25, and tend normally to elevate the latter, and these springs are of such a strength that the platform 25 will be lowered by the operation of the fly 47 in delivering the slice on to the platform, and the springs may be so proportioned that the platform will be lowered upon each operation, to an extent equal to the thickness of 115 the slice that is delivered thereto.

120 In order to retain the platform in its adjusted position during the stacking operation, one of the uprights 60, may be provided with a series of teeth 65, and a dog or pawl 130

66 is pivotally mounted upon the upright 62 to engage the teeth 65 as the platform is lowered and when it is desired to elevate the platform, all that is necessary is to trip the dog to disengage it from the teeth 65.

5 While in the present exemplification of this invention, the preferred form of construction is herein shown and described, it is to be understood that many changes may be made in the details of construction and 10 in the arrangement of the several parts without departing from the spirit of this invention.

What is claimed as new is:

15 1. The combination of a slicer, a support for the slices, and mechanism operating intermediate the slicer and the support for receiving the slices as they are cut and delivering them to the support, the said mechanism embodying a reciprocating flexible slice engaging element.

20 2. The combination of a slicer, a support for the slices, and mechanism operating intermediate the slicer and the support for receiving the slices as they are cut and delivering them to the support, the said mechanism embodying a reciprocating flexible slice engaging element, said element operated from the slicing machine.

25 3. The combination of a slicer, a support for the slices, mechanism operating intermediate the slicer and the support for receiving the slices as they are cut and delivering them to the support, the said mechanism embodying a reciprocating flexible slice engaging element, prongs on said element for engaging and holding the slice, and a fly carrier for lifting the slice from the prongs.

30 4. The combination of a slicer, and means for receiving the slice as it is cut and carrying it away from the slicer, said means embodying a flexible reciprocating slice engaging element.

35 5. The combination of a slicer, means for receiving the slice as it is cut and conveying it away from the slicer, said means embodying a flexible slice engaging element having a forward and backward movement, 40 prongs on said element penetrating the slice, and means for removing the slice from said prongs.

45 6. The combination of a slicer, a flexible slice engaging element for receiving the slice as it is cut and conveying it away, means for operating said element and permitting an interval of rest in its operation, and means operating during such interval of rest to remove the slice from said element.

50 7. The combination of a slicer, a flexible slice engaging element for receiving the slice as it is cut and conveying it away, means for operating said element and permitting an interval of rest in its operation,

55 and means operating during such interval of rest to remove the slice from said element, the said element being actuated from the slicing machine.

8. The combination of a slicer, a flexible slice engaging element for receiving the slices as they are cut and conveying them away, spaced prongs on the element penetrating the slice, a curved surface, means for causing said element to pass over said curved surface during a portion of its operation, and provision for maintaining the spaces between the slice engaging portion of the prongs against variation during the operation of the said element.

80 9. The combination of a slicer, a flexible slice engaging element for receiving the slices as they are cut and conveying them away, spaced prongs on the element penetrating the slice, a curved surface, means for causing said element to pass over said curved surface during a portion of its operation, provision for maintaining the spaces between the slice engaging portion of the prongs against variation during the operation of the said element, and means for disengaging the slice from the prongs.

90 10. The combination of a slicer, a flexible slice engaging element for receiving the slices from the cutter as they are cut, spaced prongs arranged longitudinally of the element and penetrating the slice, a curved surface, means for causing said element to carry the slice over a curved surface and then in a substantially straight plane, and provisions for maintaining the spaces between the slice engaging portion of the prongs against variation during their movement, in a straight plane and over said curved surface.

100 11. The combination of a slicer, a reciprocating flexible slice engaging element for receiving the slices from the cutter as they are cut, spaced prongs arranged longitudinally of the element and penetrating the slice, a curved surface, means for causing said element to carry the slice over said curved surface and then in a substantially straight plane, and provisions for maintaining the spaces between the slice engaging portion of the prongs against variation during the movement in a straight line and over said curved surface.

110 12. The combination of a slicer, a reciprocating flexible conveyer for receiving the slices from the cutter as they are cut, said conveyer being responsive in its movement to the operation of the slicer, prongs on the conveyer spaced from each other longitudinally of the conveyer, said prongs penetrating the slice as it is cut, means for causing the prongs to convey the slice in a curved path and then in a substantially straight path, and provisions for maintaining the spaces between the slice engaging portion

95

100

105

110

115

125

130

of the prongs against variation during their movement in the said curved path.

13. The combination of a slicer, a reciprocating flexible conveyer for receiving the 5 slices from the cutter as they are cut, said conveyer being responsive in its movement to the operation of the slicer, prongs on the conveyer spaced from each other longitudinally of the conveyer, said prongs penetrating the slice as it is cut, means for causing the prongs to convey the slice in a curved path and then in a substantially straight path, provisions for maintaining the spaces between the slice engaging portion of the 10 prongs against variation during their movement in the said curved path, said conveyer having an interval of rest in its operation, and means operating during such interval of rest, for removing the slice from the 15 20 prongs.

14. In combination, a slicing knife, means for presenting material to said knife to be sliced, spaced prongs for engaging the slice, and means for operating said prongs to 25 carry said slice away from said knife into flat position, said operating means being arranged to hold the slice engaging portions of said prongs spaced substantially uniformly from one another during said operation.

15. In combination, a slicing knife, a carriage movable relative to said knife for presenting material thereto to be sliced, a conveyer for transferring slices and having a 30 portion thereof extending in the direction of movement of said carriage and movable in unison therewith and another portion extending at an angle thereto.

16. In combination, a slicing knife, a carriage movable relative to said knife for presenting material thereto, a flexible conveyer having one run extending in the direction of movement of said carriage and another run extending away from said knife, prongs on 40 45 said conveyer for engaging the slices cut from said material, and means for maintaining the slice engaging portions of said prongs in uniform spaced relation to one another during the operation of said conveyer.

17. In combination, a slicing knife, a support for material to be sliced, said knife and support being movable relative to one another to sever slices from one face of said 50 55 material, and a flexible conveyer extending

along said face to engage said material and having a portion extending away from said knife to transfer the slices as they are formed.

18. In combination, a slicing knife, means 60 for presenting material to said knife to be sliced, a flexible conveyer having a turn in the direction thereof for transferring the slices away from said knife, prongs on said conveyer for engaging said slices, and means 65 for maintaining the slice engaging portions of said prongs at substantially the same distance from one another during the travel of said conveyer around said turn.

19. In combination, a slicing knife, means 70 for presenting material to said knife to be sliced, a conveyer for receiving the slices, a guide for changing the direction of travel of said conveyer to direct the slices away from the slicing knife, said conveyer having a 75 flexible element for coöoperating with said guide and also having prongs for engaging the slices, said prongs being arranged with their slice engaging portions in alinement with said flexible element.

20. In combination, a slicing knife, means for presenting material to said knife to be sliced, spaced prongs for engaging the slice, means for moving said prongs into engagement with said material before it is sliced, 80 means for changing the direction of movement of said prongs for carrying the material away from said knife after it has been sliced, and means for maintaining said prongs in uniform spaced relation relative 90 to one another during said operation.

21. In combination, a slicing knife, means for presenting material to said knife to be sliced, spaced prongs for engaging the slices, means for causing said prongs to engage 95 the material before it is sliced, means for moving said prongs to carry the slices away from said knife and into flat position, and means for maintaining said prongs in uniform spaced relation relative to one another 100 throughout said operation.

In testimony whereof I have signed my name to this specification, in the presence of two subscribing witnesses, on this 29th day of January A. D. 1915.

EDWARD M. STILES.
